CLAIM

The ornamental design for a motor housing for an overhead door operator, as shown and described.

DESCRIPTION

FIG. 1 is a top, front, and left perspective view of a motor housing for an overhead door operator showing our new design;

FIG. 2 is a top plan view of the motor housing for an overhead door operator as shown in FIG. 1;

FIG. 3 is a front elevational view thereof;

FIG. 4 is a left side elevational view thereof;

FIG. 5 is a right side elevational view thereof; and,

FIG. 6 is a bottom plan view thereof.

The portions of the design shown in dotted lines depict environment only and are not part of the claimed invention.
